UNITED STATES PATENT OFFICE

119,189

DESIGN FOR A GAME PIECE OR THE LIKE

Bertram Rosser, Buffalo, N. Y.

Application August 4, 1939, Serial No. 86,469

Term of patent 14 years

To all whom it may concern:

Be it known that I, Bertram Rosser, a citizen of the United States, residing at Buffalo, in the county of Erie and State of New York, have invented a new, original, and ornamental Design for a Game Piece or the like, of which the following is a specification, reference being had to the accompanying drawing, forming part thereof.

The single figure is a perspective view of a game piece or the like, showing my new design.

The numerals appearing on the design are merely illustrative.

I claim:

The ornamental design for a game piece or the like, as shown and described.

BERTRAM ROSSER.
